UNITED STATES PATENT OFFICE.

WILLIAM D. MACQUESTEN, OF MOUNT VERNON, NEW YORK, ASSIGNOR TO THE ARORA COMPANY, INC., A CORPORATION OF NEW YORK.

WASHING-MACHINE.

1,320,019.

Specification of Letters Patent. Patented Oct. 28, 1919.

Application filed November 19, 1915. Serial No. 62,410.

To all whom it may concern:

Be it known that I, WILLIAM D. MACQUESTEN, a citizen of the United States, and a resident of Mount Vernon, in the 5 county of Westchester and State of New York, have invented an Improvement in Washing-Machines, of which the following description, in connection with the accompanying drawings, is a specification, like 10 characters on the drawings representing like parts.

This invention relates to a washing machine or apparatus, especially adapted among other uses to be employed in households for effecting the family wash.

The present invention has for its object to provide a power-operated washing machine, which is simple in construction, efficient in operation, substantially inexpensive 20 and especially adapted for use with the ordinary set tubs now commonly found in households.

In accordance with this invention, an electric motor is operatively connected with a 25 reciprocating device extended down into one and preferably both tubs of a set of tubs, and said motor is also preferably connected with a wringing machine located between the tubs and extended transversely thereof.

30 Provision is made for controlling the operation of the wringer by the motor from the front of the set tubs, and provision is also made for controlling the electric motor from the front of the tubs. The reciprocating 35 devices within the tubs are preferably detachable from their operating mechanism, so that either or both can be removed from the tubs for a purpose as will be described.

These and other features of this invention 40 will be pointed out in the claims at the end of this specification.

Figure 1 is a plan view of two set tubs having applied thereto a power-operated washing machine embodying this invention.

45 Fig. 2, a front elevation of the apparatus shown in Fig. 1.

Fig. 3, a view in section and front elevation of the apparatus shown in Fig. 1.

Fig. 4, a cross-section between the tubs to 50 show the mechanism for operating the reciprocating devices within the tubs.

Fig. 5, a detail in side elevation of the clutch mechanism for coupling the wringer with the motor.

Fig. 6, a detail in front elevation on an enlarged scale of the clutch shown in Fig. 5, and

Figs. 7 and 8, details to be referred to.

Referring to the drawing, *a*, *b*, represent two set tubs of ordinary construction, such 60 as now commonly found in households. The tubs *a*, *b*, have coöperating with them a power-operated machine for washing the clothes or other articles contained in the said tubs, and preferably also a wringing machine, which is also power-operated.

In the present instance, I have shown a construction of washing machine, which is preferred by me and which is provided with devices for engaging the clothes in each of 70 the tubs *a*, *b*, said devices for each tub consisting preferably of cups 10, 12, attached to rods or bars 13, 14, which are pivotally connected to the opposite ends of a rocking frame comprising substantially parallel levers 16, 17, which are operatively connected with a rock-shaft 18 to be oscillated thereby. The cups 10, 12, and the rods 13, 14, will 75 be hereinafter referred to as plungers.

In the present instance, the lever 16 is 80 provided on opposite sides of its center with laterally extended pins or arms 20, 21, which are detachably secured to bosses 22, 23, on a cross bar 12 fast on the rock-shaft 18, see Fig. 7, and the lever 17 is provided with a 85 central pin 24, which is detachably secured to a boss 25 extended from a bracket or support 31 which also contains a bearing 26 for the rock-shaft 18.

The rock-shaft 18 constitutes a pivot for 90 the lever 16 and the pin 24 constitutes a pivot for the lever 17. The pins 20, 21, may be detachably secured to the hollow bosses 22, 23, in any suitable manner, and in the present instance this connection is effected by 95 locking pins 27 located in hollow nubs 28 on the hollow bosses 22, 23, said pins being normally forced by springs 29 into the hollow bosses so as to enter annular grooves 30 in the pins or arms 20, 21, after the manner represented in Fig. 7, and from which they may be removed by the operator pulling the pins or arms 20, 21 out of the hollow bosses 22, 23. The pivot pin 24 for the lever 17 enters its hollow boss 25 (see Fig. 8) and 100 oscillates therein.

105 Each set of plungers in each tub is actuated by its own rock-shaft 18 which is

journalized in the bearings 26 secured to the bracket or support 31 at the back side of the tubs, and each rock-shaft 18 is operatively connected to a crank-disk 32 fast on a shaft 33, which is geared to the armature shaft 34 of an electric motor 35.

In the present instance, each rock-shaft 18 is provided with a crank 36, which is joined by a connecting rod 37 with a crank pin 38 eccentrically located on the disk 32, and the shaft 33 on which said crank disk is mounted is journaled in a supporting frame 39.

The shaft 33 in the present instance has fast on it a worm gear 40, which meshes with and is driven by a worm 41 on the armature shaft 34, and said worm and worm gear preferably run in oil contained in the hollow casing or supporting frame 39. The electric motor 35 is supplied with current from a suitable source and is controlled by an electric switch 43 of known construction, which is located at the front of the tubs *a*, *b*, and is provided with an operating handle 44, which normally stands in the vertical position shown in Fig. 2 and is moved to the right when it is desired that the motor should run in one direction and is moved to the left when it is desired that the motor should run in a reverse direction.

When the circuit of the motor is closed with the plungers or reciprocating devices in their operative position, namely, coupled to the rock-shafts 18, the rotation of the shaft 33 through the crank disk 32, connecting rods 37 and cranks 36, effects oscillation of the rock-shafts 18 and the rocking frames connected therewith, consequently effecting vertical reciprocation of the plungers in each tub, for as each rock-shaft 18 is oscillated, the levers 16, 17, are oscillated or rocked and the plungers are alternately reciprocated in the tub, thereby forcing the water through the clothes and also moving the latter within the tub, and effectively washing the clothes in a minimum time and with the least possible inconvenience to the operator, who is required to do nothing but throw on the switch, and, if desired, the operator can go away and leave the machine to do its work without any attention until the clothes have been washed. When the clothes have been pounded a sufficient length of time in one water, the motor is shut off and the dirty water run off from the tubs. If desired or required clean water may be admitted into the tubs and the machine again set in motion. After the clothes have been properly washed, the rocking frames may be detached from the rock-shaft 18 and removed from the tubs, and the clothes in one tub can be transferred to the other and if desired clean water may be admitted into the tub containing the clothes. The other tub is then washed out with clean water, so as to enable it to be used as a receptacle for

the clothes after the latter have been passed through a wringing machine located between the tubs and extended transversely thereof.

The wringing machine comprises essentially a frame 50, which supports the usual rubber covered rollers 51, 52, between which the clothes are passed and subjected to the pressure of springs 53, which act to force the upper roller 52 toward the lower roller 51 in a manner well understood.

The lower roller 51 is designed to be operatively connected with the electric motor to be rotated thereby, and this result may be accomplished by a clutch mechanism, which is under the control of the operator at the front of the tubs.

In the present instance I have shown one form of clutch mechanism for coupling the roller 51 with the worm gear shaft 33. To this end, the roller 51 has affixed to its inner end, a disk 55 (see Fig. 5) provided with substantially diametrically opposite holes 56 for the reception of pins or projections 57 located substantially diametrically opposite on a disk 58, attached to a hub or sleeve 59, mounted to slide on the shaft 33 of the worm gear 40, and connected with said shaft to rotate therewith, which is effected in the present instance by a pin 60 on the shaft 33 extended into an elongated slot 61 in the hub or sleeve 59.

Provision is made for moving the clutch member or disk 58 from in front of the tubs, and for this purpose, a rod 63 is extended through the bottom 64 of the wringer frame and pivotally connected to the end of a lever 65, which is forked at its free end and entered into an annular groove 66 in the hub or sleeve 59.

By reference to Figs. 4, 5 and 6, it will be seen, that the operator in front of the tubs can couple the wringer to the motor 35, by merely pushing in the rod 63, which action turns the lever 65 on its pivot 68 so as to slide the sleeve 59 on the shaft 33 until the pins 57 on the disk or movable clutch member 58 are entered into the holes 56 in the disk or fixed clutch member 55, whereupon the motor 35 can be started, and the shaft 33 will rotate the roller 51 and the latter rotate the upper roller 52. To disconnect the wringer from the motor, it is only necessary for the operator to pull the rod 63 forward, which action turns the lever 65 and withdraws the pins 57 from the holes 56 in the disk 55.

It is preferred to provide each tub with a reciprocating device, which is operated from a power driven rock-shaft to which it is detachably connected, but it is not desired to limit the invention in this respect, as only one tub may be provided with the reciprocating device if desired.

So also, while it is preferred to use a set of alternately reciprocating plungers or

devices, it is not desired to limit the invention in this respect.

Claims.

1. In an apparatus of the character described, in combination, vertically movable devices, rocking frames carrying said devices, rock-shafts extended substantially at right angles to the vertical path of said movable devices and with relation to which said frames are axially movable to secure them to and detach them from said rock-shafts, and means for driving said rock-shafts.
2. In an apparatus of the character described, in combination, a horizontally arranged rock-shaft, a vertically movable plunger detachably secured to said rock-shaft and axially movable with relation to said rock-shaft to attach the same thereto and to detach it therefrom, and means for driving said rock-shaft.
3. In an apparatus of the character described, in combination, a horizontally arranged rock-shaft, a rocking frame detachably secured to said rock-shaft and

axially movable with relation thereto, vertically movable plungers pivoted to said rocking frame and movable in paths substantially at right angles to said axial movement, and means for driving said rock-shafts.

4. In an apparatus of the character described, in combination, receptacles open at their tops, rock-shafts supported at the rear of said receptacles and extended transversely thereof, reciprocating devices vertically movable in said receptacles, rocking frames to which said reciprocating devices are pivoted and movable axially with relation to said shafts to attach and detach said frames with and from said shafts while said reciprocating devices are in the receptacles, means for attaching said rocking frames to said shafts to cause the same to rock with the shafts and effect vertical reciprocation of said devices, and means for driving said rock-shaft.

In testimony whereof, I have signed my name to this specification.

WILLIAM D. MACQUESTEN.
